UNITED STATES PATENT OFFICE

120,041

DESIGN FOR A DRESS

Louise Decker, New York, N. Y.

Application January 22, 1940, Serial No. 89,615

Term of patent 3½ years

To all whom it may concern:

Be it known that I, Louise Decker, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is the rear view thereof on a reduced scale.

The design is characterized by the combination on the blouse portion of the specific dress disclosed of the contrasting embroidery arranged on the entire blouse in association with the facing around the neck and sleeves thereof, as shown.

I claim:

The ornamental design for a dress, substantially as shown and described.

LOUISE DECKER.
